Primary Examiner—Melody N. Brown
Attorney, Agent, or Firm—Bernhard Kretten**[57] CLAIM**

The ornamental design for a motorcycle bug deflector, as shown and described.

DESCRIPTION

FIG. 1 is a right side view of a motorcycle bug deflector showing my new design in one possible environment, the left side being a mirror image thereof;

FIG. 2 is a front view thereof;

FIG. 3 is a rear view thereof;

FIG. 4 is a bottom view thereof; and,

FIG. 5 is a top view thereof.

The broken-line showing of environmental structure in FIGS. 1 and 2 is for illustrative purposes only and forms no part of the claimed design.
